Primary Examiner — Sandra S Snapp*Assistant Examiner* — Ieisha N Price(74) *Attorney, Agent, or Firm* — Harris Beach PLLC(57) **CLAIM**

The ornamental design for a multiple caliber bore plug, as shown and described.

DESCRIPTION

FIG. 1 is a top perspective view of the multiple caliber bore plug showing my new design;

FIG. 2 is a front elevational view of the multiple caliber bore plug of FIG. 1;

FIG. 3 is a left side elevational view of the multiple caliber bore plug of FIG. 1;

FIG. 4 is a right side elevational view of the multiple caliber bore plug of FIG. 1;

FIG. 5 is a rear elevational view of the multiple caliber bore plug of FIG. 1;

FIG. 6 is a top plan view of the multiple caliber bore plug of FIG. 1; and,

FIG. 7 is a bottom plan view of the multiple caliber bore plug of FIG. 1.

The broken lines in the figures show features of the multiple caliber bore plug that form no part of the claimed design.
